UNIVERSAL PLUG BUTTON OR CLOSURE

Philip D. Becker, Hingham, Mass., assignor to
 United-Carr Fastener Corporation, Cambridge,
 Mass., a corporation of Massachusetts

Application November 17, 1948, Serial No. 60,499

4 Claims. (Cl. 220—60)

1

The present invention relates to plug buttons and closures, and more particularly to universal buttons adapted for snap fastener engagement with apertures of various diameters in supports of various thicknesses, and the invention aims generally to improve existing closures of that type.

A primary object of the invention relates to the provision of an improved plug button or closure for a support aperture, which will be of simple construction, economical of manufacture and efficient in use particularly in closures for support apertures of relatively large diameter.

A further object of the invention is the provision of an improved closure of the general type described and claimed in my copending application Serial No. 60,498, filed November 17, 1948, by providing improved means for preventing radial inward movement of the cap-supporting segments as well as to resist relative radial movement between said segments and the cap.

Other aims and objects of the invention will be apparent to persons skilled in the art from a consideration of the accompanying drawings and annexed specification illustrating and describing a preferred embodiment of the invention.

In the drawings—

Fig. 1 is a top plan view of a plug button as applied to an apertured support;

Fig. 2 is a side elevation of a plug button according to the present invention;

Fig. 3 is a bottom plan view of the plug button shown in Fig. 2;

Fig. 4 is a bottom plan view of the attaching member before capping;

Fig. 5 is a side elevation of the attaching member shown in Fig. 4;

Fig. 6 is a plan view of a half portion of a blank from which the attaching member shown in Fig. 4 is formed;

Fig. 7 is an enlarged transverse central sectional view of a plug button as taken on the line 7—7 of Fig. 3 and illustrating the button as applied to apertures of different diameter and to supports of various thicknesses;

Fig. 8 is a fragmental plan view of a blank or stamping suitable for forming an attaching member according to a modified form of the invention;

Fig. 9 is a fragmental sectional view of a plug button having an attaching member according to the form shown in Fig. 8; and

Fig. 10 is a detail side elevation of a portion of the attaching member shown in Fig. 8.

Referring to the drawings, the improved plug

2

button is preferably of two-part construction comprising an attaching member 10 and a cap member 20 which may be a closure overlying the attaching member.

3 The attaching member or fastener part 10 is preferably formed of suitable resilient sheet material, for example 40-50 carbon steel, and preferably is a stamping shaped to provide an inner central fastener supporting annulus 11, an axially spaced cap-supporting rim 13 and a plurality of resilient support-engaging fingers 15. The annulus 11 is preferably of continuous construction and may be provided with an outer peripheral bead or embossment 12 to increase the rigidity of the annulus 11.

20 The material of the attaching member surrounding the reinforcing bead 12 is preferably shaped to provide a circular series of circumferentially spaced cap-supporting rim segments 13 with integral connecting struts 14 and a circular series of resilient fastener fingers 15 interposed between certain of said segments and struts. In the illustrated embodiments as shown in Figs. 6 and 8 the outer peripheral edge portion of the 25 attaching member blank is provided with radially extending M-shaped recesses 17, thus forming opposed ends of adjacent segments 13 and intermediate support-engaging tongues 15.

30 The stamping is deformed under pressure to dispose the fastener supporting annulus 11 and the cap-supporting rim segments in axially spaced relation and preferably in substantially parallel planes. In so doing, the strut portions 14 are disposed obliquely to the annulus 11 and extend therefrom in divergent relation, and the diameter of the cap-supporting rim is materially contracted.

35 The attaching member 10, thus formed, and as shown in Figs. 4 and 5, is then capped to hold the circular series of cap-supporting segments in rigid assembly. The cap member 20 may be of any suitable type and construction, for example an annulus ring carrying a screen, lens or glass, or a continuous closure 21 overlying the cap-supporting rim depending upon the use to which the plug button is to be put. The cap 20 is conveniently secured to the rim segments 13 by crimping or clenching the outer peripheral edge portion of the cap under the segments as at 22.

40 The invention provides means for resisting relative radial movement between the cap member 20 and the supporting rim segments 13, particularly during the cap-crimping or folding operation. This may be accomplished by bending the 45 outer terminal corners of the segments angularly

3 to provide prongs 18 adapted to bite into and grip the material of the cap.

As will be apparent, the resilient support-engaging fastener members 15 are integrally joined to the annulus 11 and extend therefrom in divergent relation at a greater angle than the oblique strut portions 14. The members 15 are shaped to provide substantially flat bearing portions 15a, preferably parallel to the central axis of the button, for radial tensioned engagement with the aperture wall 5 of a relatively thick apertured support 6, as shown at the right hand side of Fig. 7. The snap fastener engagement of the fingers 15 with the apertured walls of the support is positive and secure due to the fact that the fingers 15 flex about points of support inwardly of the support, and engage the support intermediate the cap member 20 and the point of flexure. Thus, the fingers 15 are adapted to engage efficiently the aperture wall 7 of a thin support 8, as shown in the left hand side of Fig. 7, or the aperture wall 5 of thicker support 6. Secure fastening engagement is effected notwithstanding substantial variations in the diameter of the support aperture due to the substantial radial movement inherent in the fastener tongues 15.

The invention may conveniently be employed in plug buttons and closures of relatively large diameters. In cases where relatively few spring fastener fingers 15 are required for the desired fastener engagement, the intervening segments are preferably apertured or cut out or otherwise divided, as by openings 19 as shown in Figs. 2 to 5, to avoid tearing the metal as the blank is drawn to finished shape. In such case the support-engaging fingers are alternately arranged between pairs of segments 13. When, however, the number of support-engaging fasteners is substantially increased, the intervening segments may be sufficiently narrow that they may be drawn to shape without tearing, and the fingers 15 may be alternately arranged with the segments 12.

Although I have illustrated and described preferred embodiments of the invention, I do not intend to be restricted thereto as the scope of the invention is best defined by the appended claims.

I claim:

1. A plug button or closure adapted for snap fastener attachment in a support aperture, comprising a cap and a one-piece annular member having a central opening and a rim surrounding said opening, circumferentially spaced segmental sections surrounding said rim and extending obliquely therefrom, the outer terminal edges of said sections being outwardly turned providing collectively a cap-supporting rim, said cap being secured to and overlying said rim and including an inturned flange underlying said rim, cap-engaging means on said outwardly turned rim portion in engagement with said inturned flange of said cap for resisting relative radial movement between the cap and segmental sections, and resilient fastener elements formed from the metal surrounding said central rim and disposed between said segmental sections.

2. A plug button or closure adapted for snap fastener attachment in a support aperture, comprising a cap and a one-piece annular member having a central opening and a rim surrounding said opening, circumferentially spaced segmental sections surrounding said rim and extending obliquely therefrom, the outer terminal edges of

said sections being outwardly turned providing collectively a cap-supporting rim, said cap being secured to and overlying said rim and including an inturned flange underlying said rim, cap-engaging prongs on said outwardly turned rim portion in engagement with said inturned flange of said cap for resisting relative radial movement between the cap and segmental sections, and resilient fastener elements formed from the metal surrounding said central rim and disposed between said segmental sections.

3. A plug button or closure adapted for snap fastener attachment in a support aperture, comprising a cap and a one-piece circular member 15 having a central opening and a rim surrounding said opening, the body of said member surrounding said rim comprising integral circumferentially spaced segmental sections, integral fastener tongues connected to the body of said member surrounding said rim and disposed between certain of said segmental sections, portions of said segmental sections adjacent said rim extending obliquely thereto in divergent relation and providing relatively stiff connecting 20 struts, the outer peripheral edges of the sections being outwardly flanged and collectively providing an annular series of spaced cap-supporting rim portions, said cap being secured to and overlying said supporting rim portions and including an inturned flange underlying said rim, the outer peripheral corner of said segmental sections being downwardly bent providing a cap-gripping means engaging said inturned rim of said cap, and said tongues being angularly bent 25 and providing resilient support-engaging members for tensioned engagement with a wall of an aperture in which said button may be inserted.

4. A plug button or closure adapted for snap fastener attachment in a support aperture comprising a one-piece annular member, circumferentially spaced segmental sections connected to said annular member and extending angularly therefrom, the outer terminal edges of said sections being outwardly turned providing collectively a cap-supporting rim, a cap secured to and overlying said rim and including an inturned flange underlying said rim, cap-engaging means on said outwardly turned rim engaging the inturned flange of said cap for resisting relative 40 radial movement between the cap and segmental sections, and resilient fastener elements formed from the metal surrounding said central rim and disposed between said segmental sections.
